UNITED STATES PATENT OFFICE.

HARRY WEARNE, OF NEW YORK, N. Y.

DESIGN FOR A PRINTED FABRIC.

50,928.

Specification for Design. Patented June 12, 1917.

Application filed February 9, 1917. Serial No. 147,720. Term of patent 7 years.

To all whom it may concern:

Be it known that I, HARRY WEARNE, a subject of the King of Great Britain, residing in the city, county, and State of New York, have invented an ornamental Design for an Article of Manufacture, of which the following is a specification, reference being had to the accompanying drawing, forming part thereof.

The figure is a plan view of a printed fabric showing an embodiment of my new design. It is to be understood however that

my new design may be applied not only to fabrics but also to wall paper, wrapping paper, or similar articles, having surface ornamentation, without departing from what I claim as my invention.

I claim:—

The ornamental design for an article of manufacture, substantially as shown and described.

HARRY WEARNE.
